UNITED STATES PATENT OFFICE.

ANDREW F. HOWE, OF GRANITE CITY, ILLINOIS, ASSIGNOR, BY MESNE ASSIGNMENTS, TO HOWE SAFETY APPLIANCE COMPANY, OF GRANITE CITY, ILLINOIS, A CORPORATION OF ILLINOIS.

SAFETY-GUARD FOR ROTARY GRINDING-MACHINES.

1,351,908.

Specification of Letters Patent.

Patented Sept. 7, 1920.

Application filed December 27, 1918. Serial No. 268,523.

To all whom it may concern:

Be it known that I, ANDREW F. HOWE, a citizen of the United States, residing at Granite City, county of Madison, and State 5 of Illinois, have invented certain new and useful Improvements in Safety-Guards for Rotary Grinding-Machines, of which the following is a specification, reference being had to the accompanying drawings, forming 10 a part thereof.

This invention relates generally to safety devices and, more particularly, to certain new and useful improvements in safety guards for emery wheels and other rotary 15 grinding machines.

Shop practice, in either formative, corrective, or finishing processes, generally employs a high speed rotary grinding wheel, and to expedite the work and as steps are 20 made, as the art advances, toward perfection of cementing the abrasive material and perfecting the bearings or mounts of the wheel, the tendency is to increase the speed of rotation of the wheel, which now often 25 reaches five to seven thousand revolutions a minute.

In work, particles of the wheel, which is usually of emery or other suitable abrasive, are constantly being torn out and removed 30 and, under the centrifugal force developed under the high speed of rotation of the wheel, are impelled or thrown outwardly from the wheel with such force as to be a continuous source of annoyance and even 35 danger to the operator, and it is not at all uncommon for a wheel, under its high speed of rotation, to burst or "explode" and pieces thereof be thrown outwardly with such great force as to cause serious injury not 40 only to the operator, but also to workmen and objects working or standing nearby.

Numerous contrivances have been devised as simple arresters for the impelled particles of emery or other abrasive, without regard 45 for the arrest and retention of flying pieces due to bursting of the wheel; and other more or less cumbersome devices have been developed to arrest and retain the broken flying particles of an "exploding" wheel, but 50 all such devices have been found, so far as I am aware, most inefficient.

The objects of my present invention are to provide a rotary wheel-guard which is of relatively light weight and compact in form

and construction and whose "connecting-up" or installation may be readily accomplished, which, though relatively light in weight, will efficiently not only arrest flying particles of the wheel, but also withstand the strains incident to, and catch and retain 55 the broken pieces of, a bursting or exploding wheel, and which may be easily and conveniently adjusted relatively to the wheel to compensate for wheel reductions due to wear or material loss and thereby afford at 60 all times substantially the same opening for grinding space, and to generally improve upon, and simplify the construction of, 65 guards of the class mentioned.

With the above and other objects in view, 70 my invention resides in the novel features of form, construction, arrangement, and combination of parts hereinafter described and afterward pointed out in the claims.

In the accompanying drawings, 75

Figure 1 is a fragmental elevational view of a two-wheel grinding-machine equipped with safety-guards constructed in accordance with and embodying my invention;

Fig. 2 is a transverse sectional view taken 80 approximately on the line 2—2, Fig. 1;

Fig. 3 is a fragmental end elevational view of the machine illustrated in Fig. 1, portions of the wheel-guard being shown in section;

Fig. 4 is an end view of the guard illustrated as arranged upon an adjustable stand, fragmentally shown, for convenient mounting, independent of the machine, of the 85 guard upon its wheel;

Fig. 5 and 6 are plan and front elevational views, respectively, of the guard and stand shown in Fig. 4;

Fig. 7 is a perspective view of one of the brackets for conveniently fastening the 95 guard in operative position upon the grinding machine; and

Fig. 8 is a cross-sectional view of the 100 guard-stand taken approximately on the line 8—8, Fig. 6.

Referring to the drawings, in which like reference characters refer to like parts throughout the several views, and having reference now more particularly to Figs. 1, 2, and 3, my new safety-guard is illustrated 105 in connection with a standard grinding machine of double type comprising a base 1, a head 2, spaced shaft-pillows 3—3, a shaft

4 mounted for rotation on the pillows 3—3, a pulley 5 fixed on the shaft 4 intermediate the pillows 3 for belt connection with suitable power, and emery or other rotary 5 grinding wheels 6—6' mounted on the shaft 4 to rotate therewith. Such construction generally obtains in all grinding-machines and is modified only in number of grinding-wheels from a single wheel to more than 10 two, as shown. Projecting laterally from the head 2, are rigid supports 7—7, upon which are mounted suitable tool-rests 8, as best seen in Figs. 2 and 3, but which I have omitted in Fig. 1 to permit a clearer illustration 15 of other features. Each support 7 is slotted, as at 9, whereby its supported tool-rest 8 may be conveniently adjusted relatively to the particular adjacent grinding-wheel, as may be necessary or required in 20 the work.

For conveniently supporting a respective guard upon the machine, I provide a bracket 10 of substantially L-shape, one and the longer arm of the bracket being adapted 25 to rest horizontally upon a support 7 and the other or shorter arm of the bracket extending upwardly and approximately vertically adjacent the wheel. As seen in Fig. 1, where two of such brackets are employed, 30 the horizontal arm of one bracket is offset, as at 11, within its length, so that it may neatly overlie the end of the horizontal arm of the other bracket; in other particulars, the two brackets are identical in form and 35 construction. Within the length of each horizontal arm of each bracket, is a longitudinal slot 12 which intersects the slot 9 of its support 7 and through which intersecting slots 12 and 9 a bolt 13 is extended, whereby the bracket may be facilely 40 adjusted to selectively position its vertical arm with respect to the wheel, whose special relations with the supports and machine-head vary in different makes of machines. Each bracket is also provided longitudinally in its horizontal arm with an elongated slot, as at 14, through which slots 45 14 a bolt 15 may be extended to adjustably fasten together and lend rigidity to the two brackets; obviously, with a machine 50 having only one wheel, the slot 14 may be omitted or, if necessary or desired, the horizontal arm of the bracket may be reduced in length accordingly. The vertical arm of 55 each bracket is also provided longitudinally, as seen especially in Fig. 2, with a pair of spaced parallel slots 16—16, for purposes shortly appearing.

The guard proper comprises a lower half 60 or section A and an upper half or section B, each section being of hood shape and both sections being preferably of light sheet steel or other suitable metallic material. Lower section A consists of an arched rim or wall 65 17 substantially semi-circular in shape in

side elevation, and side walls 18—18 whose outer margins are correspondingly semi-circular in shape and which are preferably welded or otherwise suitably united at their side outer margins to the opposite side edges 70 of the rim or wall 17. Upper section B similarly consists of an arched rim or wall 19 and side walls 20—20, upper section B, however, being cut away or reduced at its forward end to provide a suitable grinding-space 75 in the finished guard for the work. The side walls 18 and 20 of the lower and upper sections A and B, respectively, are arcuately cut away at their inner margins as shown, to accommodate the shaft 4 transversely of the guard and also to permit adjustable shifting of the guard to operatively 80 accommodate grinding-wheels of different diameter, as more fully hereinafter appears. At the rear of the guard, the rims or walls 85 17 and 19 of the lower and upper sections A and B, respectively, are elongated preferably integrally to provide co-operating hinge-members adapted to accommodate a pin or bolt 21 for pivotally fastening the 90 sections A and B together, whereby the sections A and B may be relatively swung to facilitate the placement of the guard over and around, or removal of the guard from over and around, a grinding wheel, and 95 whereby also upper section B may be adjustably swung away from lower section A to vary the width of the grinding-space at the front of the guard as may be required or desired for the work being done. 100

22 indicates a fastening or securing plate for the guard. This plate 22 has preferably the shape or form best seen in Figs. 2 and 4 and has fixed thereto intermediate its ends a pair of transversely disposed bolts 23—23 105 which are adapted to fit the slots 16—16 of the vertical arm of the supporting bracket 10. When its bolts 23 are extended through the slots 16 and fixed to the bracket, as by the nuts 24, the plate 22 forms or provides 110 a rigid, non-rocking connection between the guard and bracket, such connection being adapted for adjustment as may be required to compensate for non-uniformity in vertical spacing between the wheel-shaft and 115 tool-support in the various makes or types of grinding-machines. At its forward end, plate 22 is substantially longitudinally slotted, as at 25, to adjustably receive a fastening-bolt 26 fixed to, and projecting transversely from, the inner side wall 18 of the lower section A of the guard. At its rear end, the plate 22 is provided with a second slot, as at 27, adapted to adjustably receive 120 one end of the hinge-pintle or bolt 21. The bolts 26 and 21 with their nuts thus provide a rigid connection between the guard as a whole and the plate 22, which connection is also adapted for adjustment to compensate for wheel wear, said connection permitting 130

convenient shifting of the guard as a whole relatively to the plate 22 and the inclosed wheel, so that the guard may at all times be properly related to the wheel and as the 5 wheel is worn and reduced diametrically, brought nearer to the wheel at its grinding space where the work is brought to the wheel.

Pivottally fastened at its lower end to the 10 plate 22, as seen particularly in Figs. 2 and 4, is an arcual arm 28 provided within its length with a corresponding arcual slot, as at 29, adapted to adjustably fit and accommodate a bolt 30 threaded into a side wall 20 of upper section B. By means of the arm 28 and its described connection with the upper guard-section B, the section B may be 15 releasably locked in any selected position to the plate 22 and also locked in any selected 20 adjustably swung position relatively to the lower guard-section A.

For arresting sparks and particles flying from the wheel, I provide an arrester which is substantially in the form of a shield comprising a main wall 31 having the shape 25 best seen in Fig. 3, and side walls or ears 32—32. This shield is disposed upon the upper guard-section B at its forward or free end, as shown, and is pivottally fastened adjustably at its walls 32 to the side walls 20 of the said guard-section, the shield being carried upon the guard-section with its main wall 31 disposed at such an angle 30 to the forward edge of the rim 19 of the guard-section as to stop and deflect inwardly 35 away from the operator any flying wheel-sparks or particles. The shield being pivoted adjustably, as described, upon the upper guard-section, it may be conveniently 40 swingably adjusted relatively to the guard and fastened at selective angles upon the guard-section B so as to properly perform its function as the position of the guard-section B is changed or shifted relatively 45 to the inclosed wheel. The rim 17 of lower guard-section A is provided with an aperture, as at 33, forming an outlet from the guard for the arrested sparks and particles.

Disposed upon the outer side wall 18 of 50 the lower guard-section A, is a plate 34 provided with a slot, as at 35, in which a plurality of fastening-bolts 36 projected through said guard-wall 18 are adapted to fit for adjustably securing the plate to the 55 guard. Extending from the plate 34, preferably as a rigid integral extension thereof, is a cage 37 adapted to surround and guard the projecting end of the shaft 4.

In use or operation, and first in installing 60 a guard over and upon a wheel, upper section B is swung outwardly away from lower section A, the guard then placed in inclosing position upon the wheel, and the bolts 23 of its securing plate 22 then fastened to 65 the vertical arm of the supporting bracket

10, the guard as a whole being adjusted, by means of the bolts 26 and 21 and coöperating slots 25 and 27, approximately concentric with the wheel and its shaft 4. The upper section B is then swingably adjusted 70 relatively to lower guard-section A as may be required in regulating the grinding-space at the forward part of the guard and then locked selectively in such position by means of the arm 28 and its fastening bolt 75 30, the arrester being correspondingly adjusted, as before described, relatively to the upper guard-section B. The plate 34 and its shaft-cage 37 are then fastened upon the guard, with cage 37 correspondingly concentric with, and inclosing the outer or free end of, the wheel-shaft 4. With the guard in such operative position, it will be evident that the wheel and its shaft are substantially fully inclosed, with resulting safety 80 to the operator, the guard and its arrester serving not only to prevent injury to the operator by flying sparks, particles, and the like, but the guard itself serving efficiently to arrest and retain, and thereby prevent 90 injury to adjacent persons or objects by, the outwardly impelled parts of an exploding or bursting wheel.

As the inclosed wheel is diametrically reduced through wear, the slots 26 and 21 permit a ready shifting of the guard as a whole 95 relatively to the inclosed wheel and the relatively fixed plate 22 to bring the grinding-space of the guard into convenient working position to the reduced wheel, as indicated by the dot-and-dash lines in Fig. 2. And since such adjustment or shifting of the guard would obviously decenter the cage 37 relatively to the shaft, and since the cage 37 should be operatively approximately concentric with shaft 4 at all times, I provide 100 the plate 34 with the slot 35, before described, which correspondingly permits ready adjustment of the cage 37 relatively to the shaft, and for such purpose I provide 105 an extra bolt-hole, as at 38, in the lower guard-section A to accommodate one of the cage-securing bolts 36 in any required extreme adjustment of the cage. On any such shifting of the guard, the upper section B 110 may be swingably adjusted relatively to lower guard-section A, as may be required, and conveniently locked in such adjusted position, the arrester also being conveniently adjusted relatively to the reduced wheel as 120 may be required on such shifting of the guard as a whole or on the adjustment of upper guard-section B only.

In some instances, it may be desirable to 125 support the guard independently of the machine; hence I provide for such purpose a stand such as shown in Figs. 4, 5, and 6, which includes a bracket, taking the place of the described machine-brackets, comprising a base 39, rising vertically from and upon 130

opposite sides of which are ears 40 and 41 disposed somewhat obliquely to each other, as best seen in Fig. 4, the ear 40 corresponding to the described vertical arm of the machine bracket and being correspondingly slotted to adjustably receive the bolts 23, and the ear 41 being slotted or apertured, as at 42, to receive one end of the guard-pintle 21. With such bracket, the guard may be 10 bodily moved or shifted for purposes of adjustment to the wheel in the same manner as has been described in connection with the machine brackets. Depending from base 39 is a preferably non-circular stem 15 43, and by preference the base 39, ears 40 and 41, and stem 43 are formed as an integral unit. The stand proper, used in connection with the bracket just described, comprises a column 44 having supporting feet 20 45, which may be fixed to the floor near the wheel-stand or machine base or frame, the column 44 being longitudinally cored to receive the post 43 of the bracket, which bracket may be held in altitudinal adjusted 25 positions relatively to the column by means of one or more set-screws or the like 46 seated in the column, as shown, to engage the stem 43.

I am aware that minor changes in the 30 form, construction, arrangement, and combination of the several parts of my new safety-guard may be made and substituted for those herein shown and described without departing from the nature and principle 35 of my invention.

Having thus described my invention, what I claim and desire to secure by Letters Patent is:

1. A grinding-wheel safety-guard comprising a pair of hood-shaped sections 40 cooperating to inclose the wheel, in combination with means for supporting the guard as a whole around the wheel, said means including a separate plate having connection 45 with a side wall of one of the sections.

2. A grinding-wheel safety-guard comprising a pair of hood-shaped sections 50 cooperating to inclose the wheel, in combination with means for adjustably supporting the guard as a whole around the wheel, said means including a separate plate having an 55 adjustable connection with a side wall of one of the sections.

3. A grinding-wheel safety-guard comprising a pair of hood-shaped sections and a 55 pin hingedly connecting the sections together to inclose the wheel, in combination with means for supporting the guard as a whole around the wheel, said means including a separate plate having connection with the pin and with one of the sections.

4. A grinding-wheel safety-guard comprising a pair of hood-shaped sections and a 65 pin hingedly connecting the sections together to inclose the wheel, in combination

with means for adjustably supporting the guard as a whole around the wheel, said means including a separate plate provided with slots, the plate having connection at said slots with the pin and with one of the 70 sections.

5. A grinding-wheel safety-guard comprising a pair of hood-shaped sections co-operating to inclose the wheel, in combination with means for adjustably supporting 75 the guard around the wheel, said means including a bracket, and a separate plate fastened to the bracket, the plate being provided with slots and having adjustable connection at its slots with the guard. 80

6. A grinding-wheel safety-guard comprising a pair of cooperating hood-shaped connected sections adapted for operatively inclosing the guard, in combination with supporting means affording adjustments of 85 the guard to inclose the wheel, said means including a bracket, and a plate fastened to the guard and adapted for adjustable engagement with the bracket.

7. A grinding-wheel safety-guard including a pair of hood-shaped sections hingedly connected to inclose the wheel, in combination with a supporting plate fastened to one 95 of the sections, and an arm having connection with the plate and with the other section for locking said other section against hinged movement relatively to the first section. 90

8. A grinding-wheel safety-guard including a pair of hood-shaped sections hingedly connected to inclose the wheel, in combination with a supporting plate fastened to one 100 of the sections, and an arm having pivoted connection with the plate and adjustable connection with the other section for adjustably locking said other section against hinged 105 movement relatively to the first section. 100

9. A grinding-wheel safety-guard comprising, in combination, a pair of co-operating hood-shaped connected sections adapted for operatively inclosing the wheel, means 110 for supporting the guard adjustably around the wheel, whereby the guard may be bodily shifted relatively to the inclosed wheel, and a shaft-end cage mounted adjustably upon the guard, whereby said cage may be adjustably shifted relatively to the shaft-end on 115 adjustments of the guard relatively to the inclosed wheel.

10. A grinding-wheel safety-guard comprising, in combination, a pair of hood-shaped sections co-operating to inclose the wheel, means for supporting the guard adjustably around the wheel, whereby the guard may be bodily shifted relatively to the inclosed wheel, and a shaft-end cage having 125 a slotted extension adjustably fastened at its slot to one of the guard-sections, whereby said cage may be shifted relatively to the shaft-end on 130 adjustments of the guard relatively to the inclosed wheel. 130

11. The combination with a support, of a bracket having an adjustable connection with the support, a plate having an adjustable connection with the bracket, a grinding-
5 wheel mounted for rotation on the support, and a guard inclosing the wheel, the guard having an adjustable connection with the plate.
12. The combination with a grinding-
10 wheel, of a support, a safety-guard comprising a pair of hood-shaped sections and a pin hingedly connecting the sections to inclose the wheel, a plate having connection with one of the sections and with the pin, and a pair of spaced brackets on the support, the 15 plate having engagement with one of the brackets and the pin having engagement with the other bracket.

In testimony whereof, I have signed my name to this specification.

ANDREW F. HOWE.
